UNITED STATES PATENT OFFICE.

HIRAM H. BICKFORD, OF ELMIRA, NEW YORK.

APPARATUS FOR TEMPERING OR HARDENING STEEL.

No. 820,619.

Specification of Letters Patent.

Patented May 15, 1906.

Application filed June 6, 1905. Serial No. 263,970.

To all whom it may concern:

Be it known that I, HIRAM H. BICKFORD, a citizen of the United States, residing at Elmira, in the county of Chemung and State of New York, have invented certain new and useful Improvements in Apparatus for Tempering or Hardening Steel, of which the following is a specification.

This invention relates to improvements in apparatus for tempering or hardening tools or implements of steel where it is required that certain portions thereof shall be of hard metal and others of soft metal in one homogeneous piece, and has to do more particularly with an apparatus to be used in preparing saw-blades, such as described in my Letters Patent No. 657,155, dated September 4, 1900.

The object of my invention is to provide means for shielding certain portions of the metal from contact with the tempering or hardening liquid and retaining such portions while in contact with the liquid at approximately the same temperature to which the metal was heated before submitting it to the liquid bath.

I attain my object by means of an apparatus arranged and operated substantially in the manner illustrated in the accompanying drawings, in which—

Figure 1 represents a side view of an apparatus particularly designed for tempering or hardening the alternate sections of the aforesaid saw-blades; Fig. 2, an end elevation of the same, showing the manner of suspending the apparatus over the bath and with one end of the shield-clamp sectioned on the line *x x* in Fig. 1; Fig. 3, a detail showing a section through the shields on line *y y* in Fig. 1, and Fig. 4 a detail showing a portion of an enlarged section on the line *x x* in Fig. 1.

Like letters of reference designate like parts in the several views.

The apparatus, as herein illustrated, comprises a frame made up of a pair of longitudinally-disposed angle-bars A A, along the under side of which are arranged pipes B. The angle-bars are attached near each end to pairs of levers C, which are coupled together by hinge-joints at D. At the top the levers are coupled to toggle-arms E, which are coupled to short arms projecting from opposite sides of the shaft S, said shaft being provided with a hand-lever F, whereby the shaft may be rotated to draw the levers C together, thereby throwing the pipes B apart to admit a plate L, which is to form a saw-blade be-

tween the chambered shields K, which are attached to and depend from said pipes.

The apparatus is suspended by chains or cables G from an overhead carrier, whereby it may be elevated from the bath-tank N and moved to one side thereof. By way of illustration I have shown these chains in Fig. 2 as passing over a pair of sprocket-wheels H with counterbalancing-weights I attached to the free ends. At each end the sprocket-shafts are provided with sprocket-wheels which ride on supporting-racks J. This arrangement, however, is shown here merely by way of illustration of one way to operate the device. When the plate L is in position between the clamping-shields, the parts will assume the positions shown in Fig. 2, and it will be noted that the toggle-arms E are inclined downwardly, so that the weight of the apparatus as it hangs from the chains G will act through said arms to force said shields into close gripping engagement with the plate.

From the pipes B passages run to the chambers on each side of the plate formed by the hollow shields K, said passages being provided with valves at M, the stems of which valves project inwardly, so as to engage the faces of the plate when the shields are in clamping position to open the valves. When the shields are thrown away from the plate, the valves will be closed by the pressure of the air which passes through the pipes B. This air is delivered to said pipes from a source of supply through a central pipe W, from which branch pipes T pass from a swivel-joint U to the pipes B at each side of the apparatus. A valve V is interposed for shutting off the air-supply.

At one side of the tank N, I have indicated a table or bench at O upon which the plates L will be delivered from a heating-furnace to the tempering apparatus. At the end of this table adjacent to the tank I provide an upending device for the plates, which consists of upright stationary arms R and one or more trip-arms Q, operated by a lever P. By this device as the plates are passed along the table O in horizontal position they will be brought up against the uprights R, and by pulling down upon the lever P the arm Q will throw said plates into vertical position, as indicated at L.

In the operation of tempering after a plate heated to the required degree of temperature has been placed in position by the trip at the end of the bench O the shield will be moved

into position with the jaws open over the plate. By throwing down the hand-lever F the shield-jaws K will be brought into gripping engagement with the sides of the plate. 5 A movement to the left, as the apparatus is shown in Fig. 2, will drop the plate, protected at alternating sections by the shield-jaws K, into the cooling-bath N. Air, preferably at a high temperature, so as not to 10 chill the protected sections of the plate, will be delivered from pipes B to the shield-chambers at a pressure just sufficient to keep the liquid of the bath from entering the chambers. A slight leakage of the air will take 15 place around the edges of the jaws K, and this will cause a sufficient circulation of heated air in contact with the protected portions of the plate to maintain said portions at approximately the same temperature while in 20 the bath. After being immersed in the bath a sufficient length of time the apparatus will be raised therefrom and moved to the right, the shield-jaws opened, and the plate dropped therefrom between the tank and the 25 bench O, after which another plate will be taken from the bench and the operation repeated. Instead of submerging the plates in the bath the bath may be so arranged as to have the cooling liquid sprayed against 30 the plates.

While this apparatus is more particularly designed for use in the manufacture of saw-blades of the type described from plates of high carbon steel, I do not wish to be confined to this application of it. The idea of 35 protecting certain portions of a plate, bar, or body of metal from contact with a tempering or hardening liquid and excluding the liquid

therefrom by air I believe to be new. Moreover, the apparatus may be constructed in 40 various ways to adapt it to the tempering or hardening of various tools and appliances where the metal is required to be hard in certain portions and soft in others.

Therefore what I claim as my invention, 45 and desire to secure by Letters Patent, is—

1. In combination with a tempering or hardening bath, means for protecting certain portions of a plate, bar or other body of metal, while subjected to the bath, from contact with the liquid of the bath and excluding said liquid from said protected portions by air delivered to the protected surfaces from a source of supply.

2. The combination, with a tempering or hardening bath, of a hollow shield adapted to form an air-chamber when in contact with the surface of a plate, bar or other body of metal, which is to be subjected to the bath, and means for supplying said chamber with 50 air, at such a pressure that the liquid of the bath will be excluded therefrom.

3. The combination, with a tempering or hardening bath, of a plurality of hollow shields, means for clamping said shields upon 55 opposite sides of the plate, bar or other body of metal which is to be subjected to the bath, and means for delivering air to the chambers so formed at a pressure sufficient to exclude 60 the liquid of the bath.

In testimony whereof I have affixed my 70 signature in presence of two witnesses.

H. H. BICKFORD,
